CLAIM

The ornamental design for a support for holding objects at the front of a camera, as shown and described.

DESCRIPTION

FIG. 1 is a top front right perspective view of a support for holding objects at the front of a camera attached to environment showing our new design;

FIG. 2 is a top front right perspective view shown in use with environment thereof;

FIG. 3 is a top front right perspective view thereof;

FIG. 4 is a top rear left perspective view thereof;

FIG. 5 is a front view thereof;

FIG. 6 is a side view thereof; and,

FIG. 7 is a rear view.

The broken lines in the drawings depict environment, and form no part of the claimed design.

1 Claim, 4 Drawing Sheets
